UNITED STATES PATENT OFFICE.

HUGH FRANCIS FULLAGAR, OF GATESHEAD, ENGLAND.

INTERNAL-COMBUSTION ENGINE.

1,199,538.

Specification of Letters Patent. Patented Sept. 26, 1916.

Application filed April 10, 1915. Serial No. 20,455.

To all whom it may concern:

Be it known that I, HUGH FRANCIS FULLAGAR, a subject of the King of Great Britain and Ireland, residing at Gateshead-on-Tyne, in the county of Durham, England, have invented Improvements in Internal-Combustion Engines, of which the following is a specification.

This invention relates to internal combustion engines specially suitable for propelling aeroplanes. In an engine for this purpose it is very desirable that all the reactions of the engine should be self contained and give rise to no external force tending to distort or set up vibration in the relatively light fuselage and furthermore that the gyrostatic effect of the revolving masses shall neutralize each other so that change in the direction of flight in one plane shall produce no tendency to a further change in the direction of flight in another plane. In an engine to which the present invention is applied, these objects are attained by dividing the power of the engine, preferably equally, between two parallel or approximately parallel shafts to each of which a propeller can be attached, so that by the revolution of the shafts in opposite directions the gyrostatic effect of the revolving masses and torque reactions on the engine frame can be neutralized, while the reciprocating parts are so disposed that their inertia forces are completely balanced and tendency of stresses produced by the explosions to set up vibration in the engine frame is eliminated. In its simplest form such an engine comprises an open ended cylinder having two oppositely moving pistons each connected to one of a pair of parallel crank shafts at either end of the cylinder. The two shafts are kept in phase by any suitable form of mechanical gearing, such as a lay shaft and helical wheels, a sprocket chain or chains and gearing, or cranks and connecting link rods. Since the two shafts are rotated in opposite directions their torque reactions neutralize each other and have no tendency to rotate the engine as a whole relatively to either shaft, while the gyrostatic effect of the two shafts and of any propellers, fly wheels or other weights they may carry will also neutralize each other. Moreover the reciprocating parts attached to the shafts having exactly opposite motions, their inertia forces will similarly balance each other, while the fluid pressure acting equally upon

the opposed pistons will have little or no tendency to set up vibrations in the engine frame. For aeroplane purposes this construction would give rise to an impracticable engine of too large dimensions and too great a weight and to overcome these disadvantages and at the same time to produce a double acting two stroke engine with a more uniform turning effort, which is the object of the present invention, there is or are employed one or more pairs of open ended cylinders, the cylinders in each pair being placed closely side by side and each provided with two oppositely moving pistons, the pistons of each cylinder being cross connected to the pistons of the other cylinder of the pair.

In the accompanying drawings Figures 1 and 2 are respectively a sectional elevation and plan, more or less diagrammatic of one form of engine according to the invention, Fig. 3 is a similar view to Fig. 2 of a modified form of engine according to the invention.

As shown in Figs. 1 and 2 the engine may comprise, as a unit, two cylinders *a*, *a*¹ placed closely side by side and each provided with two opposed oppositely moving pistons *b* which are cross connected, the piston at one end of each cylinder being connected by means of a pair of oblique tie rods *i* to the piston at the opposite end of the other cylinder. *e* are propellers on the crank shafts, *g* is a lay shaft and *h* helical gearing connecting the lay shaft to the crank shafts. The pistons of one cylinder only, namely *a*, are directly connected by the connecting rods *f* to the crank shafts *d* by means of a single crank *c* on each shaft, the impulses from the pistons in the conjugate cylinder *a*¹ being transmitted to the two crank shafts through the oblique tie rods *i* and connecting rods *f*. Although not so restricted, the pair of cylinders *a*, *a*¹ are shown situated with their axes in a plane at right angles to the common plane containing the axes of the crank shafts. In every case where one pair of pistons is directly coupled to the crank shafts, as in Figs. 1 and 2, the cross heads *k* of the other pair may, as shown, conveniently be utilized to operate each as one member of an air pump working in connection with a stationary member, shown as a pump cylinder *m*, to supply the charges of air to the respective pair of cylinders *a*, *a*¹ in the manner described in the

specification of a former application for Letters Patent Serial No. 785539 filed 19th August 1913. *n* are compressed air receiver chambers that receive air from the pumps 5 and deliver it into the cylinders *a*, *a'* through ports *o* controlled by the pistons *b* as usual. *p* are exhaust ports and *q* exhaust chambers. The complete engine may consist of any convenient number of such units 10 placed side by side. In Figs. 1 and 2 two such units are shown working on the two shafts *d*, *d'* through two pairs of cranks, the cranks *c*, *c'* in each pair being shown 90° apart, in which case each crank receives two 15 impulses per revolution and each shaft four impulses per revolution at 90° apart.

As an alternative to the cross connection of the pistons by means of oblique tie rods, the cylinders of each pair may be twisted 20 through a half turn around each other at the middle of their length, as shown in Fig. 3, so as to bring the piston *b* at one end of each cylinder into line with the piston *b'* at the opposite end of the adjacent cylinder in 25 which case the tie rods *i* connecting the pistons will be parallel to the axis of the connected pistons instead of oblique thereto. This method of cross connection is fully described in the specification of former Letters Patent granted to me No. 995858 dated 30 June 20th, 1911.

For the purpose of this specification the term cylinder is intended to include any form of hollow inclosing member having 35 cylindrical end portions for the reception of a pair of oppositely movable pistons, whether such end portions have their axes in alinement or are displaced so as to be parallel or inclined to one another so long as 40 the arrangement is such that when two members of this kind are placed side by side, the piston at one end of one member shall move in the same direction as the piston at the opposite end of the other member 45 thereby enabling them to be coupled together for connection to a single crank, and in the claims hereunto appended a pair of cylinders embraces a pair of operative members as herein defined.

50 What I claim is:—

1. An internal combustion engine comprising two oppositely revoluble shafts arranged side by side, cranks thereon, a pair of cylinders also arranged side by side situated between the shafts, two oppositely movable pistons in each cylinder, coupling rods cross connecting the piston in one cylinder to the opposite pistons in the other cylinder, and means for transmitting motion 55 from the two pairs of cross connected pistons separately to the respective crank shafts. 60

2. An internal combustion engine com-

prising a pair of cylinders arranged side by side, a pair of coacting crank shafts adapted to revolve in opposite directions, 65 two oppositely disposed pistons in each cylinder adapted to move in opposite directions, means separately connecting the pistons in one cylinder to the crank shafts and means separately connecting the non-corresponding pistons in the other cylinder with the pistons in the first named cylinder. 70

3. An internal combustion engine comprising a pair of cylinders arranged side by side, a pair of co-acting crank shafts adapted to revolve in opposite directions, two oppositely disposed pistons in each cylinder adapted to move in opposite directions, means embodying rods arranged obliquely to the axes of the cylinders connecting each 80 piston of one cylinder with the oppositely situated piston of the other cylinder and a rod coupling each such cross connected pair of pistons to one of the crank shafts corresponding thereto, whereby an explosion in 85 any one cylinder simultaneously transmits an effort to the cranks of both shafts urging them in opposite directions. 90

4. An internal combustion engine comprising two oppositely revoluble shafts arranged side by side, cranks thereon, a pair of cylinders situated between the shafts both ends of one cylinder of the pair being closed to act as cross head guides and pump chambers, crossheads in the form of pump 95 pistons movable in such closed ends of the cylinders, two oppositely movable engine pistons in each cylinder, coupling rods cross connecting the engine pistons in one cylinder to the crossheads of the pistons in the other cylinder and means for transmitting motion from the two pairs of cross connected pistons and crossheads separately to the respective crank shafts. 100

5. An internal combustion engine comprising two oppositely revoluble shafts arranged side by side, cranks thereon, a pair of cylinders also arranged side by side situated between the shafts, two oppositely movable pistons in each cylinder, coupling rods cross connecting the pistons in one cylinder to the opposite pistons in the other cylinder, means for transmitting motion from the two pairs of cross connected pistons separately to the respective crank 110 shafts, and gearing between the said shafts in order to maintain them in proper phase relationship. 115

Signed at Newcastle-upon-Tyne England this 16th day of March 1915.

HUGH FRANCIS FULLAGAR.
